UNITED STATES PATENT OFFICE.

FREDERICK A. PRESTON, OF HIGHLAND PARK, ILLINOIS, ASSIGNOR TO THE P. & M. CO., OF CHICAGO, ILLINOIS, A CORPORATION OF ILLINOIS.

TWO-WAY ANTICREEPER.

1,118,229.

Specification of Letters Patent. Patented Nov. 24, 1914.

Application filed November 22, 1911. Serial No. 661,788.

To all whom it may concern:

Be it known that I, FREDERICK A. PRESTON, a citizen of the United States, residing at Highland Park, in the county of Lake 5 and State of Illinois, have invented new and useful Improvements in Two-Way Anti-creepers, of which the following is a full, clear, concise, and exact description, reference being had to the accompanying drawing, forming a part of this specification.

My invention relates to an anti-creeping device for preventing creeping of rails either in one direction or in two directions.

One of the objects of the invention is to 15 provide means which may be applied to a tie to coöperate with a device for frictionally engaging the rail base to prevent creeping.

Another object is to provide a device for 20 frictionally gripping the rail base and co-operating with a member secured to two or more ties so that said member transmits to said ties the thrust due to a creeping tendency either in one direction or two directions.

A further object is to provide means for 25 maintaining constant the distance between the ends of adjacent ties opposite a rail joint where the joints are arranged in staggered relation.

An additional object is to provide a combined tie-plate and anti-creeper.

Further objects will be apparent from the description which follows.

The invention may be embodied in various forms.

In the accompanying drawings I have 30 illustrated several forms which have certain practical advantages. I do not desire to limit myself, however, to the particular forms illustrated.

In the drawings: Figure 1 is a top plan view of a portion of a railway track including a rail joint and a combined two-way 45 anti-creeper and tie-plate, opposite said rail joint. Fig. 2 is a top plan view of a different form of combined anti-creeper and device for holding the ties the proper distance apart. Fig. 3 is an elevation partly in section, taken on the line 3—3 of Fig. 2. Fig. 4 is a side elevation of the device shown in Fig. 2. Fig. 5 is an elevation of a modified detail. Fig. 6 is an elevation of another

form of modified detail. Fig. 7 is a top plan view of a combined tie-plate and one-way 55 anti-creeper. Fig. 8 is a top plan view of a modified form of a two-way anti-creeper and tie-holder. Fig. 9 is a side elevation thereof. Fig. 10 is a top plan view of a one-way 60 anti-creeper. Fig. 11 is a top plan view of 65 a two-way anti-creeper one member of which is adapted to bear directly against the tie to resist the creeping tendency in one direction. Fig. 12 is a side elevation thereof.

A common arrangement of the rails is 65 illustrated in Fig. 1. The rail joint on one side is opposite or near the middle portion of the rail on the other side. In other words, the rail joints have a staggered arrangement. The ends of the rails 1, 1 are joined by the 70 usual rail joint 2. The rail joint is about opposite the middle of the opposite rail 3. The fish-plates comprising a part of the rail joint structure are bolted to the rail 1 in the usual manner and are also spiked to the 75 ties 4. Consequently the rail joint acts as an anti-creeper as any creeping tendency of the rail in either direction is resisted by both ties. Unless the creeping tendency of the other rail 3 is also resisted by the opposite 80 ends of the same two ties, the ends of the ties which support the rail joint will be thrust in one direction or the other causing a skewing of said ties. As a result the gage 85 may be disturbed, the rails being brought nearer together by the skewing action of the ties.

To prevent the above objectionable action, I provide preferably as in the construction shown in Fig. 1, a tie-connecting plate 5 90 which rests on two ties and is spiked thereto. I apply to the rail 3 any suitable type of friction gripping device 6 adapted to increase its hold on the rail base through a properly applied thrust. In the arrangement illustrated, the friction device 6 comprises two rail gripping members having an interlocking wedging engagement beneath the rail base, as explained more in detail in connection with another figure. The rail 100 gripping members coöperate preferably at diagonally opposite corners with shoulders 7 on the plate 5. As a result, when the rail 3 tends to creep to the left, for example, as seen in Fig. 1, the upper clamping member 105 6 bears firmly against the shoulder 7 to

resist the creeping, the reaction against said member 6 being in a direction tending to draw both members 6 closely together and thereby increase their grip on the rail base. 5 When the rail 3 tends to creep to the right, as seen in Fig. 1, the lower clamping member 6 abuts against the corresponding lower shoulder 7, whereupon the same increased gripping action occurs and the thrust of 10 the rail is transmitted to the ties through the spikes. As a result of the fact that the creeping tendency of the rails is resisted by both ends of the ties 4, said ties are crowded firmly against the ballast throughout sub- 15 stantially their entire length, whereby said creeping is effectually resisted, and furthermore, the thrust applied to one end of said ties being substantially the same as that applied to the other end thereof, there is little 20 or no skewing tendency.

In the construction shown in Fig. 2 the rail-clamping members 6 are substantially the same as those illustrated in Fig. 1. Each member 6, however, coöperates with a separate member 8 to resist creeping. These latter members are preferably duplicates of each other and one of them prevents creeping in one direction, while the other prevents creeping in the other direction, both 25 members having shoulders 7 similar to those previously described against which the rail-clamping members 6 are adapted to abut. These members, of course, may assume various forms, their function being to resist 30 creeping of the rail in either direction by transmitting the thrust from the clamping members to the ties. The members 8 are preferably spiked at each end to the ties by spikes 9 which are provided in addition 35 to the usual spikes 10 for securing the rail to the tie. I do not limit myself to this arrangement, of course, as it is not essential that both ends be secured. Each plate, at 40 one end, may preferably abut against one of the spikes 10. The thrust delivered by that 45 end of the member 8 is, therefore, distributed over two spikes instead of one. I do not limit myself to this arrangement, however.

50 Referring more particularly to the clamping members 6, it should be noticed that each member grips one side of the rail base, said members having an interlocking engagement beneath the rail base, as seen more 55 particularly in Fig. 3, the engagement being along a line somewhat diagonal with respect to the length of the rail, as seen in dotted lines in Fig. 2. These members are applied to the rail base by driving first one 60 member on to the rail base by blows directed at right angles to the length of the rail, and then driving the second member against the opposite side of the rail base in a similar manner and adjacent to the first 65 member. Either or both members may then

be driven toward the other by blows applied parallel to the rail. It is preferable, however, to confine this longitudinal movement to the smaller of the two clamping members 6. As the members are driven together their 70 interlocking walls 11 cause both members to be drawn toward each other to increase their grip on the rail base. It is apparent that after said members have been driven together as far as possible, that they engage 75 the rail base with a very firm frictional engagement. Any pressure brought to bear against either member in the same direction as that in which said member was driven to secure the wedging engagement of the parts, 80 will result in increasing still further the frictional engagement of both members on the rail base. It will be apparent, therefore, that any creeping tendency of the rail in one direction will cause the flange 12 of 85 one member to press against the shoulder 7 of the corresponding spacing member 8, resulting not only in preventing creeping of the rail, but resulting also in an increased gripping tendency of the interlocking members 6. Similarly a creeping tendency in 90 the opposite direction will be resisted by the opposite member 8. It is understood, of course, that the spacing members 8 are not spiked to the ties until after the clamping 95 members 6 have been applied to the rail, for obvious reasons.

From an inspection of Figs. 3 and 4 it will be seen that the flanges or shoulders 12 project both above and below the spacing 100 member 8. This construction permits considerable vertical play between the clamping members and the engaging projections 7 on the members 8. This insures proper engagement of the parts, even though the rail 105 should spring up and down somewhat, due to passing trains, and even though the rail should wear down into the tie, as often happens. The shoulders or flanges 12 are preferably slightly concave or cut in. See Fig. 110 4. This construction tends to increase the security of the engagement between said shoulders and the abutting portion 7, as it tends to prevent said portion 7 from slipping over said shoulder 12 either above or 115 below, as might possibly occur in extreme instances of vertical play.

It is desirable under certain circumstances to relieve the spikes of the thrust due to the creeping tendency. Accordingly I may provide the spacing members 8 with downwardly projecting tongues or shoulders, as shown in Figs. 5 and 6. In Fig. 5 the spacing member 8, which may be assumed to be a steel plate, is provided with a lug 13 struck 120 therefrom and bent downwardly, as shown, to engage the side of the tie. In Fig. 6 the spacing member 8 may be assumed to be made of malleable iron and is provided with a reinforced shoulder 14 for a similar pur- 125

pose. The two shoulders 13 and 14 illustrated will suggest various other forms of shoulders which may be designed as adapted to meet varying requirements. Such 5 shoulders may be used not only with the form of device illustrated in Fig. 2, but also with the other forms illustrated, and in fact with any suitable equivalent device.

Referring further to Fig. 2, it will be 10 apparent that when the creeping tendency is being properly resisted by both ties, the wide end of whichever spacing member 8 is receiving the creeping thrust, will be put under compression, the other half of said member or the narrow end thereof will be put under tension. It will be apparent further that while it is desirable it is not essential that each member 8 be put under both compression and tension, when acting to resist creeping. In other words, it is not essential that the creeping be resisted equally by both ties. Consequently, either spacing member 8 may be designed to act under compression only or to act under tension only. 15 One way to do this would be to provide an elongated slot or spike opening in one end or the other of the tie-spacing member 8. Furthermore, in cases where the tie-spacing feature did not happen to be important the 20 device could be used as an anti-creep only by employing the clamping members 6 and connecting them to an adjacent tie by a compression member or a tension member which would extend from said tie only to 25 said clamping members. It is also apparent from Fig. 2 that where it is desired to prevent creeping in one direction only, it will be necessary to use only one spacing member 8, the other being omitted entirely. Under 30 these circumstances it will not be necessary to provide both clamping members 6 with a shoulder 12. Such a construction is more fully referred to hereinafter.

Fig. 7 illustrates a combined anti-creep, 35 tie-plate and tie connector similar in general to that shown in Fig. 1, but adapted to resist creeping in one direction only. In this figure the plate 15 extends beneath the rail at each tie and, therefore, acts as a tie-plate at both ends. One of the clamping members 6 is provided with the shoulder 12, the other clamping member being constructed without said shoulder. In assembling the device the clamping members 6 are first applied to the rail in the manner 50 previously described. The rail is then lifted and the connector 15 is then slipped under the rail and eventually spiked to the ties with the notched portion 16 firmly engaged 55 by the shoulder 12.

In the form of device shown in Figs. 8 and 9 two similar metal strips or bars 17 are provided, adapted to have their ends spiked to adjacent ties and having their 60 middle portions twisted into vertical planes.

The middle portion is provided with a slot 18. Each slot is adapted to receive a projecting wing or shoulder 19 on one of the clamping members 6. The parts are assembled with each wing 19 bearing against 70 the end wall of the corresponding slot. It will be apparent from the preceding description that creeping is resisted in both directions by this arrangement. It will be further apparent that this device may be used 75 as a one-way anti-creep.

Fig. 10 illustrates a one-way anti-creep without the tie-plate feature. The operation of this form of device will be apparent in view of the preceding description.

Figs. 11 and 12 illustrate a two-way anti-creep in which one member is provided with an extension or jaw 12 similar to that already described in connection with the preceding figures. The clamping member 6 85 is provided with a downwardly extending flange 20 which abuts against the adjacent cross-tie 4 and thereby transmits to said tie directly the thrust due to a creeping tendency in one direction. The creeping tendency in the other direction is resisted preferably by both ties through the plate 8 in a manner which will be apparent in view of the foregoing description.

From the foregoing description it will be 95 apparent that all the constructions illustrated comprise a device for frictionally gripping a rail and adapted to increase its grip when pressure is properly applied to one portion or another portion thereof. Co-operating 100 with this device in most cases is a member for transferring the thrust to an adjacent tie, usually to two or more ties. Some of the devices illustrated prevent creeping in one direction and some in both directions, 105 depending on whether the anti-creep is designed to be applied to a rail having tendencies to creep in one or two directions. It is apparent that the features illustrated in connection with one form may be used 110 in connection with some other form of device. Therefore, I do not desire to limit myself to the use of any one feature with the particular type of device with which it is illustrated. Neither do I intend to limit 115 such use to the various other forms illustrated, as further forms may be devised, which fall within the scope of the invention.

It is to be understood that while the form of rail gripping members illustrated is a desirable one, I have illustrated this form simply as typical of a frictional clamping device, as distinguished from a device which moves with the rail due to the fact that it is bolted thereto or engages notches therein, 120 or is otherwise in positive engagement therewith. I desire to cover, therefore, in combination with the other elements of the device any means for frictionally gripping the rail, as distinguished from a device hav- 125 130

ing positive engagement therewith. There are various types of such devices already developed in the prior art and, of course, still further types may be developed to meet special requirements. The foregoing description will render clear to those skilled in the art the manner in which such various types may be made to co-act with the other elements of the combination required in carrying out the desired function.

I desire, in general, to be understood as having used the various terms throughout the specification in a descriptive and not in a limiting sense, and I desire to cover broadly any suitable equivalent means for accomplishing the desired result, as long as said means fall within the scope of the appended claims.

I claim as my invention:

1. In an anti-creeper, a unitary device complete in itself for frictionally gripping a rail base between adjacent ties, and additional independent means coöperating with said device and with a cross-tie to transmit any thrust due to a creeping tendency of said rail, to said tie.

2. In an anti-creeper, a device independent of the use of bolts for frictionally gripping a rail base between adjacent ties, and additional independent means coöperating with said device and with both of said ties to transmit any thrust due to a creeping tendency of said rail, to said tie.

3. In combination, a boltless device for frictionally gripping a rail base between adjacent ties, and additional independent means coöperating with said device and with a tie to prevent creeping of said rail in either direction, said rail being restrained entirely by the frictional engagement therewith of said device.

4. In combination, a boltless device for frictionally gripping a rail base between adjacent ties, and additional independent means coöperating with said device and with both ties to prevent creeping of said rail in either direction, said rail being restrained entirely by the frictional engagement therewith of said device.

5. In combination, an anti-creeper adapted to be applied to a rail and ties opposite a rail joint, to prevent skewing of said ties, including a device for frictionally gripping the rail and coöperating members on each side of said rail each secured at opposite ends to one of said ties, the pressure exerted by said device on said coöperating members due to creeping of the rail in either direction, tending to increase the frictional grip of said device on the rail.

6. An anti-creeper comprising means complete in itself, adapted to be secured to a rail base and to maintain its hold thereon entirely by its frictional engagement therewith, said means having a shoulder thereon,

and a member secured to an adjacent tie and having an abutment engaging said shoulder whereby said member is put under tension by the creeping tendency of the rail in the proper direction.

70

7. An anti-creeper comprising means frictionally applied to a rail base, and a retaining member coöperating therewith but separate therefrom, and secured to an adjacent tie to resist the creeping tendency of the rail and to increase the frictional hold of said means on said rail.

8. An anti-creeper comprising a plurality of members, having wedging engagement along a line diagonal with respect to the length of a rail, two of said members having rail-gripping jaws, certain of said members having a projecting flange adapted to be engaged by a member other than a tie to resist creeping.

85

9. An anti-creeper comprising coöperating members having interlocking wedging engagement beneath the rail base, and having substantially vertical projecting bearing faces of substantial height, said bearing faces, when said members are in assembled position, being arranged diagonally with respect to each other.

10. An anti-creeper comprising among its members a device having a rail-gripping jaw and having a projecting flange with a concave bearing face.

11. A combined tie-plate and anti-creeper comprising a plate adapted to rest on a plurality of ties, and a device for frictionally engaging the base of a rail comprising a plurality of members interlocked with each other and adapted to increase their interlocking engagement upon relative movement in the proper direction, said members coöperating with said plate whereby a creeping tendency of the rail tends to produce such relative movement.

100

12. In combination, means frictionally secured to a rail so as to move therewith, and a tie-plate arranged beneath the rail and secured to a plurality of ties, said means being independent of said tie plate but coöperating therewith whereby the thrust due to a creeping tendency of the rail is transmitted to and resisted by all of said ties.

110

13. In combination, means extending across the base of a rail and secured thereto so as to move therewith, and a tie-plate arranged beneath said rail and secured to a tie, said tie-plate having an opening therein, said means projecting into said opening and engaging the wall of said opening whereby the thrust due to a creeping tendency of the rail is transmitted to and resisted by said tie.

120

14. A railroad track having opposite the joint in one line of rails a tie plate under an intermediate part of the opposite rail, said tie plate bridging two ties and having an

125

130

abutment, and a rail anchor positioned against said abutment; substantially as described.

15. A railroad track having opposite the joint in one line of rails a member bridging a plurality of ties, and suitably secured thereto, and a rail anchor applied to one of the rails and coöperating with said member to transmit the creeping thrust of the rail thereto.

16. In a railroad track having staggered rails, an anti-creeping device applied to an intermediate portion of a rail substantially opposite a rail joint, and a member suitably secured to the same ties which support at their opposite ends the rail joint, said member having a substantially vertical face against which said rail anchor abuts.

17. In a device of the character described, a member adapted to rest on a plurality of ties and be suitably secured thereto to maintain them in spaced relation, and an anti-creeping device arranged adjacent to said member and adapted to maintain a frictional hold on a rail base, said member having a bearing face against which said anti-creeping device abuts to transmit to said member the thrust due to a creeping tendency of the rail, the reaction causing said anti-creeping device to increase its grip on said base.

18. A device of the character described comprising a member lying parallel with a track rail and securable to a tie, in combination with a rail anchor comprising transversely interwedging members for preventing material longitudinal movement of the rail.

19. In combination with a railway rail, a rail anchor clip, a rail anchor mate adapted for transverse wedging engagement therewith, whereby both may be caused to grip said rail, and a plate for locking one of said rail anchor members and thereby the other to a tie.

20. In a device of the character described, a rail anchor comprising interwedging members frictionally gripping a rail base be-

tween adjacent ties, and additional means coöperating with said anchor and with a cross tie to transmit any thrust due to a creeping tendency of said rail, to said tie.

21. In a device of the character described, and in combination, a rail anchor member adapted to engage one side of the rail base, a rail anchor member adapted to engage the opposite side of the rail base, said members being interwedged, and means securable to a railway tie and adapted to restrain one of said members from movement. 60

22. In a device of the character described, coacting rail anchor members independent of the use of bolts for frictionally gripping a rail base between adjacent ties, and additional means coöperating with said device and with both of said ties to transmit any thrust due to a creeping tendency of said rail, to said tie.

23. In combination, means adapted to be secured to a rail, so as to move therewith, and a tie-plate arranged beneath said rail and secured to a tie, said tie-plate having an opening therein extending at least the width of the rail base beneath the latter, said means projecting downwardly under said rail base into said opening and engaging a wall thereof, whereby the thrust due to a creeping tendency of the rail is transmitted to said tie through said tie-plate. 75

24. The combination with an anti-creeper which extends across the base of a rail and grips both flanges thereof, of a plate located between the rail and the tie and secured to the latter, said plate having an opening therein of sufficient width to accommodate the portion of the anti-creeper which projects lower than the rail base, said portion coöperating with a wall of said opening to transmit the creeping thrust to said plate.

In witness whereof, I have hereunto subscribed my name in the presence of two witnesses.

FREDERICK A. PRESTON.

GEO. B. JONES.

It is hereby certified that in Letters Patent No. 1,118,229, granted November 24, 1914, upon the application of Frederick A. Preston, of Highland Park, Illinois, for an improvement in "Two-Way Anticreepers," errors appear in the printed specification requiring correction as follows: Page 1, line 28, for the letter and word "o fadjacent" read *of adjacent*; page 3, line 13, for the word "receiving" read *receiving*; and that the said Letters Patent should be read with these corrections therein that the same may conform to the record of the case in the Patent Office.

Signed and sealed this 15th day of December, A. D., 1914.

[SEAL.]

J. T. NEWTON,

Acting Commissioner of Patents.
